United States Patent Office

Des. 204,049
Patented Mar. 15, 1966

204,049

RESIDENCE MARKER

Russell F. Hardy, Hulman Bldg., Dayton, Ohio

Filed Sept. 15, 1964, Ser. No. 81,734

Term of patent 14 years

(Cl. D1—12)

FIG-1

FIG. 1 is a front elevational view of a residence marker showing my new design;

FIG. 2 is a side elevational view thereof;

FIG. 3 is a cross sectional view taken on line 3—3 of FIG. 1.

The dominant features of my design reside in the portions shown in full lines.

I claim:

The ornamental design for a residence marker, substantially as shown and described.
